UNITED STATES PATENT OFFICE.

THOMAS A. PEEBLES, OF PITTSBURGH, PENNSYLVANIA.

PRESSURE-CONTROL SYSTEM.

Application filed September 3, 1925. Serial No. 54,350.

This invention relates to the use of fluid pressure and more particularly to a control system for fluid pressure lines such, for example, as the steam pressure lines in general 5 use.

Due to the increased economy in the operation of high pressure steam turbines and engines over those operated at low pressures, it is now customary in installing new boilers, 10 to put in those which operate at a materially higher pressure than that at which the old boilers operate, and steam consuming units designed to work at the higher pressure are likewise installed for use in connection with 15 the new boilers. As a result many plants must maintain two systems working at different pressure when in operation.

Due to the improved design of the new, high pressure boilers and the better means 20 for securing complete combustion, the new boilers are always more economical than the old low pressure boilers. For the most economical operation of such a plant it is, therefore, desirable that the greatest possible 25 amount of steam pressure for both the high and low pressure systems be supplied from the high pressure boilers, thereby reducing the amount of coal which must be burned under the less efficient low pressure boilers.

30 An object of this invention is to provide a control system for delivering pressure from a high to a low pressure system in accordance with the demand upon the latter, but wherein such supply is reduced in accordance with a 35 predetermined drop in the pressure of the high pressure system so as to prevent drainage by the low pressure system should the demand upon the latter be greater than the high pressure system can meet in addition to the 40 requirements of the high pressure steam consuming units.

A further object is to provide a system for 45 delivering fluid pressure to a low from a high pressure system of such arrangement that the high pressure system will be safeguarded against the low pressure system becoming a drain upon it so that a decrease in the pressure of the former which would prevent the high pressure consuming units from operating 50 efficiently will be avoided.

A still further object is to provide a mechanism for the purpose set forth wherein a valve 55 which permits the flow of pressure from a high to a low pressure line is so controlled that the flow is proportional to the demand upon the low pressure line as long as the pres-

sure of the high pressure line is above a pre-determined point, but wherein the flow is reduced in proportion to a drop in the pressure in the high pressure line below such pre-determined point. 60

These and other objects which will be apparent to those skilled in this particular art are accomplished by means of this invention, one embodiment of which is illustrated in 65 the accompanying drawing which illustrates a preferred arrangement of an apparatus adapted to accomplish the hereinbefore set forth objects.

The mechanism illustrated is shown in connection with two pressure supply lines, one of which ordinarily carries steam or other fluid at high pressure from the high pressure boilers to the high pressure consuming units and the other of which carries steam at low 70 pressure from the low pressure boilers to the low pressure consuming units. A connection between the two lines is provided with a valve by means of which the low pressure line is adapted to be supplied from the high pressure line so that all pressure consuming units 75 can be supplied from the more economically operated high pressure boilers. Mechanism is provided for opening this valve in proportion to the decrease in pressure of the low 80 pressure line but in order to prevent the low pressure units from being a drain upon the high pressure line and preventing the steam being delivered to the high pressure units at the pressure necessary for efficient operation, 85 means are provided for closing the valve in proportion to the decrease in pressure of the high pressure line when it falls below a certain predetermined point, and if such pressure continues to fall the valve will be closed 90 altogether. 95

The control system which is illustrated in the accompanying drawing is shown as applied to a high pressure steam line 1 which is adapted to supply high pressure steam consuming units from modern high pressure boilers (not shown) and it is connected to a low pressure steam line 2 through a connection 3 which is provided with a valve such as the butterfly valve 4 for controlling or cutting off the flow of pressure from the high to low pressure line. The valve is operated by an arm 5 having a weight 6 connected to its end in such a manner that the weight tends to open the valve. The arm 5 is also secured 100 to a cable 7 running over pulleys 8 and connected to one end of a valve actuating lever 9. 105

which is mounted upon a pivot 10 provided on any suitable support 11.

A pin 12 is secured to the valve actuating lever 9 adjacent the opposite end thereof and 5 is received within a slot 13 formed in a connecting link 14 which extends upwardly from one end of a lever 15 pivoted to a bracket 16 upon the support 11. The opposite end of the lever 15 is connected by a link 17 to any 10 desired form of pressure regulator 18 such, for example, as the regulator shown in the patent to Hopwood No. 1,371,243 granted March 15, 1921. In the present case the link 17 connects the lever 15 with the reciprocating 15 cross head 19 of the Hopwood regulator and this regulator is connected to the high pressure line 1 by a connecting line 19' for transmitting the pressure of the line 1 to the regulator so as to move the valve actuating 20 lever to close the valve when the pressure in this line falls below a certain point, as will be hereinafter more fully set forth.

A second pin 20 is mounted in the end of the lever 9 adjacent the pin 12, and the pin 25 20 is received within the slot 21 of a connecting link 22, the lower end of which is secured to a lever 23 pivoted in a bracket 24 on the support 11. The opposite end of the lever 23 is connected by a link 25 to the cross head 26 of a second pressure regulator such as the Hopwood regulator 27 which is similar in all respects to the high pressure regulator 18 but which is connected to the low pressure steam line 2 by a connecting line 27' for transmitting the pressure of the line 2 to the regulator in such a way that a decrease in the pressure of this line causes the regulator 27 to move the valve actuating lever 9 so as to open the connecting valve 4.

40 The high pressure regulator 18 is adjusted in the well known manner so that a decrease of the pressure in the high pressure line 1 with which it is associated below a set predetermined point will cause the cross head 19 to move downwardly. This raises the connecting link 14 so as to oscillate the valve actuating lever 9 in such a way as to move the valve 4 toward its closed position. Such movement will be proportional to the decrease in 45 pressure of the high pressure line 1 and if such pressure drops sufficiently the valve 4 will be closed entirely, thus preventing the low pressure line 2 from draining the line 1 below the pressure at which the high pressure consuming units operate efficiently. Ordinarily, when the pressure in the line 1 is above a predetermined point, the cross head 19 is maintained in its elevated position so that the end of the slot 13 of the connecting link 14 is positioned well below the pin 12, thus permitting the pin 20 to contact with the end of the slot 21 in the connecting link 22.

45 The low pressure regulator 27 is associated with the low pressure line 2 in such a way that when the pressure in the line drops the cross

head 26 moves upwardly so that the connecting link 22 is lowered and permitting the valve actuating lever 9 and the valve 4 to be moved by the weight 6 in such a way as to open the valve 4.

70 It will thus be seen that so long as there is sufficient pressure in the high pressure line to supply the low pressure consuming units without draining pressure away from the high pressure consuming units connected to 75 the line 1 the valve will be open for the passage of steam pressure from the high pressure line to the low pressure line, and this opening will be proportional to the decrease in pressure of the low pressure line 2. Should the line 2 take so much pressure from the high pressure line as to prevent the efficient operation of the high pressure consuming units the control 18 will be actuated so as to close the valve 4 in proportion to the drop in pressure of the line 1 below this point and if necessary the valve 4 will be closed altogether so as to insure the high pressure consuming units being supplied with steam at the most efficient operating pressure,

90 Although I have described this invention in connection with the use of steam pressure it can obviously be applied to any system of fluid pressure.

95 What I claim as new and desire to secure by Letters Patent is:—

1. The combination of a high pressure line, a low pressure line adapted to be supplied with fluid pressure from said high pressure line, means for regulating the high pressure flow in accordance with the demand upon said low pressure line while the pressure of said high pressure line is maintained above a predetermined point and means for regulating said flow in accordance with the pressure of said high pressure line when its pressure drops below said predetermined point.

100 2. The combination with a fluid pressure system of a valve for diverting the flow from said system to a second system, means responsive to the demand of said second system for regulating said valve and means responsive to the pressure of said first system for regulating said valve when said pressure reaches a predetermined minimum.

110 3. The combination of a high pressure system, a low pressure system, a valve connecting said systems, means responsive to the pressure of said low pressure system for controlling said valve so as to divert fluid pressure to said low from said high pressure system when the pressure of said low pressure system falls below a predetermined minimum and means responsive to the pressure of said high pressure system for controlling said valve when the pressure of said high pressure system reaches a predetermined minimum.

120 4. The combination of a high pressure line, a low pressure line, a connection between 125

said lines provided with a valve, means for controlling said valve in response to variations in pressure in said low pressure line so as to supply said line with pressure from said high pressure line when required and means responsive to variations in pressure in said high pressure line for controlling said valve when the pressure in said line reaches a predetermined minimum.

5 10 5. The combination of a high pressure system, a low pressure system, a valve adapted to divert fluid pressure from said high to said low pressure system, means responsive to a decrease in the pressure of said low pressure system for opening said valve and means responsive to a decrease in the pressure of said high pressure system for controlling said valve.

15 20 6. The combination in a fluid pressure system of a high pressure system, a low pressure system, a valve connecting said systems, mechanism responsive to variations in the pressure of said low pressure system for opening said valve so as to divert pressure to said low pressure system from said high pressure system and means responsive to variations in the pressure of said high pressure system for rendering said mechanism ineffective.

25 30 7. The combination of a high pressure line, a low pressure line, a valve connecting said lines, a lever for opening and closing said valve, means responsive to a decrease in the pressure of said low pressure line for moving said lever so as to open said valve and permit a pressure flow from said high to said low pressure line in proportion to said decrease and means responsive to a decrease in the pressure of said high pressure line for moving said lever so as to close said valve in proportion thereto, the connections between said pressure responsive means and said lever being independently operable.

35 40 45 8. The combination of a high pressure line, a low pressure line, a valve connecting said lines, a lever for opening and closing said valve, mechanism provided with a lost motion connection to said lever and responsive to a decrease in the pressure of said low pressure line for moving said lever to open said

valve and permit a pressure flow from said high to said low pressure line in proportion to said decrease, mechanism provided with a lost motion connection to said lever and responsive to a decrease in the pressure of said high pressure line for moving said lever so as to close said valve in proportion thereto, the connections between said mechanisms and said lever being independently operable.

5 10 55 9. The combination of a high pressure line, a low pressure line, a valve connecting said lines, a lever for opening and closing said valve, mechanism having a pin and slot connection to said lever and responsive to variations in the pressure of said low pressure lines for shifting said lever so as to operate said valve to vary the flow from said high to said low pressure line and mechanism having a pin and slot connection to said lever and responsive to a decrease in the pressure of said high pressure line for shifting said lever independently of said first named mechanism so as to close said valve in proportion to said decrease and prevent the draining of said high by said low pressure line.

60 65 70 75 10. The combination of a high pressure system, a low pressure system, a valve connecting said systems, means responsive to variations in the pressure of said low pressure system for operating said valve so as to divert more or less fluid pressure from said high to said low pressure system and means responsive to a predetermined variation in the pressure of said high pressure system for operating said valve.

80 85 90 95 11. The combination of a high pressure system, a low pressure system, means responsive to variations in the pressure of said low pressure system for diverting fluid pressure from said high to said low pressure system and means responsive to predetermined variations in the pressure of said high pressure system for preventing draining of said high pressure system so as to maintain operating pressure therein.

In testimony whereof, I have hereunto subscribed my name this 31st day of August, 1925.

THOMAS A. PEEBLES.
